UNITED STATES PATENT OFFICE.

WILLIAM WHIGHAM, OF PITTSBURGH, PENNSYLVANIA.

RAILWAY-TRACK CONSTRUCTION.

1,045,108.

Specification of Letters Patent.

Patented Nov. 19, 1912.

Application filed December 9, 1911. Serial No. 664,780.

To all whom it may concern:

Be it known that I, WILLIAM WHIGHAM, a citizen of the United States, residing at Pittsburgh, in the county of Allegheny and 5 State of Pennsylvania, have invented certain new and useful Improvements in Railway-Track Constructions, of which the following is a specification.

My invention relates to the construction 10 of railway ties and the fastenings employed to secure the track rails in place on the ties of a railway track.

One object of my invention is to provide 15 a rail fastening of novel construction having an improved arrangement of parts whereby the rails are rigidly held against vertical and transverse movement on the rail seats of the ties and another object of this invention is to provide novel means for 20 securing rails in place on the ties of a railway track by the use of which free lengthwise movement of the track rails on the ties is afforded.

A further object of my invention is to 25 provide a railway tie having improved means for maintaining the ties in place on the road bed of the railway track, and a still further object of the invention is to provide a railway track construction having im- 30 proved means whereby the track rails are insulated from the railway ties and from each other.

Further objects of my invention will appear hereinafter as the invention is more 35 fully described.

Referring to the accompanying drawings forming part of this specification, Figure 1 is a longitudinal side elevation showing an insulated railway tie having the track rails 40 secured in place thereon and showing the rail fastening forming part of this invention as applied for use in securing the track rails to the ties. Fig. 2 is a plan of the apparatus shown in Fig. 1. Fig. 3 is a sec- 45 tional side elevation showing a detail, on an enlarged scale, of the tie and rail fastening as applied thereto, the track rail being shown in sectional end elevation. Fig. 4 is a sectional end elevation, on an enlarged 50 scale, of the rail tie and rail fastening, the section being taken on the irregular line IV-IV of Fig. 3. Fig. 5 is a top plan and Fig. 6 is a side elevation, on an enlarged 55 scale, showing in detail the keepers by which the track rails are secured in place on the

ties. Fig. 7 is a sectional end elevation of the keepers shown in Figs. 5 and 6. Fig. 8 is a sectional detail showing the relative position of the hook flanges and the keepers prior to the insertion of the keepers into 60 place in fastening the track rails in position on the ties.

In the drawings, A designates the rail tie having rail chairs B secured thereto beneath the track rail C, the tie plates D and 65 the keepers E being employed to secure the rails C in place on the rail chairs B in accordance with my invention. In the construction shown the track rails C and tie plates D are insulated from the rail chairs 70 B and ties A by sheets of suitable insulating material F.

The tie A as shown is trough-shaped in cross section and has a base formed by the horizontal web portion 2 which is intermediate of the vertically extending flange portions 3, 3, which project upwardly from the top surface of the base and the horizontally extending base portions 4, 4, which project beyond the vertical flanges 3 on the 75 outside of these flanges so as to widen the base of the tie and provide a large bearing surface which contacts with the ballast of the road bed of the railway track. The flange extensions 4, 4, are made of a width 80 and thickness which will transmit all loads put thereon to the road bed without any tendency to bend or curve upwardly around the root of the tie flanges at the intersection of the flanges 3 with the base portions 4. 85 The rail chairs B also are channel-shaped in cross section and have downwardly extending flanges 5, 5, projecting from two opposite marginal side edges of the integral horizontal web member 6. The flanges 5 have 90 short integral extensions 7 projecting upwardly above the top surface of the web member 6 so as to form a recessed seat for the tie plates D secured on the upper surface of the chairs B.

The outer surfaces of the tapering flanges 5, 5, on the rail chairs preferably are parallel and the inner faces of the vertically extending tapering flanges 3 on the tie also are made parallel, the over all width of the 95 rail chairs B being such that the flanges 5 fit snugly between the parallel inner surfaces of the flanges 3 on the tie, the toes of the flanges 5 engaging with the upper surface of the web member 2 of the tie. Rivets 100 105

8 or equivalent fastening means are employed to rigidly secure the rail chairs B to the tie A.

The rail chairs B are provided with tie plates D which are permanently secured in place on the chairs. Preferably the rail chairs and tie plates are assembled in place on the ties in the shop in readiness for use in constructing a railway track. The tie plates D as shown have a horizontal web member 9 with oppositely extending hook flanges 10 and 11 projecting from each of two marginal side edges. The downwardly and inwardly extending hook flanges 10, which are rolled or otherwise formed so as to be straight or only partially bent when applied to the rail chairs are further bent and are caused to embrace and tightly engage the web member 6 of the rail chairs B, the contacting marginal side edges of the member 6 being rounded to the same curvature as on the inner sides of the recesses formed by the hook flanges 10.

This construction is of particular value in forming a tie construction in which the track rails and tie plates are insulated electrically from the ties and rail chairs. In the construction shown, sheets 12, 12, of vulcanized rubber, wood fiber or other insulating material are inserted between the opposing faces of the rail chairs B and the tie plates D. Two opposite marginal side edges 13 of the insulating material 12 are turned upwardly so as to be interposed between the inner surfaces of the flange extension 7 in the rail chairs B and the adjacent marginal side edges of the web 9 forming part of the tie plate D. One marginal edge 14 of each piece 12 of insulation F is bent around the rounded edge on opposite sides of the web 6 of the rail chairs B so as to prevent the hooked flanges 10 on the tie plates having a metallic contact with the rail chairs B. Reference to the drawings will show that by this construction the rail chairs and ties are effectually insulated from the tie plates and rails and that the insulation is covered by the rail flanges, the keepers and the tie plates, so as to be practically entirely protected from the weather by the metallic portions of the track construction. The insulating material being permanently secured in place need not be removed nor disturbed in adjusting the gage or in re-placing the track rails on the rail ties.

When it is not desired or is unnecessary to insulate the track rails from the tie the insulating material F is omitted, the hooked flanges 10 and the under surface of the web member 9 of the tie plates being in direct contact with the rail chairs B. In such cases the hook flanges 11, 11, may be formed integral on the rail chairs so as to dispense with the tie plates, or the tie plates may be fastened to the rail chairs by rivets or

equivalent securing means so as to dispense with the hook flanges 10, 10.

The upwardly and inwardly extending hooked flanges 11, 11, on the top surface of the tie plates are utilized to secure and hold the keepers E in place on the tie plates and in holding engagement with the flanges 15 of the track rails. The keepers E have lips 16 which engage with the marginal edges of the flanges 15 on the track rails in such manner that the track rails, while securely held against vertical and transverse or side-wise movement, are free to expand or move lengthwise on the rail ties. The keepers, which have parallel faces between short tapered end portions 17 are grooved or provided with a depression 18 in their upper surfaces, the keepers being engaged by the hooked flanges 11 and held in place thereby in a manner peculiar to and forming a novel feature of this invention. Proper drainage of the trough-shaped tie is provided for by the holes 19 located in the base at intervals in the length of the tie.

As will be seen by reference to Fig. 3, one longitudinal side edge of the keepers is curved or rounded to conform with the curvature on the interior of the hook formed by the flanges 11, and the keepers are lessened in thickness at the bottom of the depression 18 in their upper surface which is engaged by the toe or marginal side edge of the hook flanges 11. One side edge of the keepers has an overhanging lip 16 which engages with the upper face of the flanges 10 on the track rails.

In constructing the track the hook flanges 11 on the tie plates D are bent inwardly and downwardly toward the upper face of the web portion 6 so that before the keepers E are driven into position to secure the rails in place on the ties, the vertical distance defining the least width of the under cut recess formed on the tie plate by the hook flanges 11 is somewhat less than the least thickness of the keepers E, and in inserting the keepers the toe of the flanges 11 must be sprung upwardly so as to tightly grasp and hold the keepers in position. After the keepers are driven lengthwise in place the corners of the hooked flanges 11 will spring downwardly sufficiently to be approximately in contact with the upper surfaces of the tapering end portions of the keepers E, this downward springing of the corner portions of the hook flanges serving to maintain the keepers in place after being inserted.

The chairs and tie plates are permanently secured in place on the ties in the shop and when used, the insulating material is also permanently secured in place in the shop. The ties, with the chairs and tie plates assembled thereon, later are placed in the road bed of the railway and the track rails are mounted on the tie plates. The keepers

E are then inserted in place in the grooves formed by the hooked flanges 11 and as the corners of the hooked flanges will spring downwardly endwise movement of the keepers on the tie plates D is prevented.

When after being put into use in a railway track it becomes necessary to remove the keepers in replacing or adjusting the keepers of the track rails, the keepers are driven out of their seats on the rail chairs. Should, upon replacing the keepers, it be found they are not held with sufficient tightness by the hooked flanges 11, they are again removed and the toes of the flanges are bent downwardly slightly farther by striking with a sledge. The keepers are then re-inserted and in this way the tie plates are readily made to compensate for slight irregularities in the thickness and contour of the keepers occurring in rolling or caused by wear occasioned by frequent removals from the tie plates.

The advantages of my invention will be apparent to those skilled in the art. By the use of the novel construction forming my invention, a rail fastening is provided in which the use of bolts and nuts is avoided and made unnecessary. The track rails are securely held against vertical and sidewise movement, while permitting free longitudinal movement of the rails on the ties. The peculiar cross section of the ties provides ample bearing surface on the tie for engagement with the road bed of the railway track. By placing ballast in the trough-shaped tie, weight which is easily removed when necessary is added to the tie so as to more securely maintain the ties in place in the road bed. The rail securing means are firmly held in place and are easily and quickly removed in making adjustments or renewals of the rails.

Modifications in the construction and arrangement of the parts may be made without departing from my invention. Instead of using keepers on each side of the rail, the tie plate may be constructed with a hooked flange engaging one rail flange, in such case a single keeper being employed to secure the rail in place by engagement with the opposite rail flange, and other changes may be made without departing from my invention as defined in the claims.

I claim:—

1. In a railway track construction a rail tie having rail securing paired hook flanges thereon, track rails extending between the hook flanges of opposite pairs, and a rail keeper having oppositely tapering end portions and extending lengthwise between the rail flange and hook flange on the tie to secure the rails on said tie, said keeper being clamped to the tie by the hook flange, the ends of said hook flange being inclined downwardly to engage the surfaces of the

tapering end portions on said keeper in preventing lengthwise movement thereof.

2. In a railway track construction a rail tie, rail chairs secured thereto, a tie plate having hook flanges, track rails extending between opposite hook flanges on the tie plate, means engaging with the rail flanges and said hook flanges to secure the rails to the tie, means insulating the tie plate from the rail chair and tie, and hook flanges on the tie plate engaging the rail chair to secure the tie plate thereon, said hook flanges securing the insulating means in place between the rail chair and tie plates. 70

3. In a railway track construction a rail tie, rail chairs secured thereto, a tie plate having hook flanges, track rails extending between opposite hook flanges on the tie plate, means engaging with the rail flanges and said hook flanges to secure the rails to the tie, and hook flanges on the tie plate engaging the rail chair to secure the tie plate thereon. 80

4. In a railway track construction the combination with a tie having vertical flanges projecting upwardly from the tie base, rail chairs having vertical flanges projecting downwardly from the horizontally extending web portion thereof, and means fastening said flanges together to secure the rail chairs on the tie, of a tie plate having downwardly and inwardly extending flanges embracing the web of said chairs to secure the tie plate in place thereon, and means detachably securing the rails to said tie plate. 90

5. In a railway track construction the combination with a tie having vertical flanges projecting upwardly from the tie base, rail chairs having vertical flanges projecting downwardly from the horizontally extending web portion thereof, said flanges being fastened together to secure the rail chairs on the tie, of a tie plate having downwardly and inwardly extending flanges embracing the web of the chairs to secure the tie plate in place thereon, means for insulating the rail chairs from the tie plate, and means detachably securing the rails to said tie plate. 105

6. In a railway track construction the combination with a trough-shaped tie having a base formed integral with vertically extending flanges, trough-shaped chairs having a horizontal web with integral downwardly extending flanges, said flanges being secured to the flanges on the rail tie, a tie plate having integral oppositely projecting hook flanges on the marginal edges of a horizontal web, the downwardly projecting hook flanges on opposite edges of the tie plate being bent into clamping engagement with the web of the rail chairs to secure the tie plates in place thereon. 115

7. In a railway track construction the combination with a trough-shaped tie hav- 130

ing a base formed integral with vertically extending flanges, trough-shaped rail chairs having a horizontal web with integral downwardly extending flanges, said flanges being secured to the flanges on the rail tie, a tie plate having integral oppositely projecting hook flanges on the marginal edges of a horizontal web, the downwardly projecting hook flanges on opposite edges of the tie plate being bent into clamping engagement with the web of the rail chairs to secure the tie plates in place thereon, and keepers extending between the upwardly extending hook flanges on the tie plate and the flanges of the rail to engage and detachably secure the rails in place thereon, said keepers being held in place by frictional engagement with the engaging hook flanges on the tie plates.

8. In a railway track construction the combination with a trough-shaped tie having vertically extending flanges, trough-shaped rail chairs having a horizontal web and downwardly extending flanges secured to the flanges of the rail tie, a tie plate having oppositely projecting hook flanges on the marginal edges of a horizontal web, the downwardly projecting hook flanges on opposite edges of the tie plate being bent around the web of the rail chairs to secure the tie plates in place thereon, and keepers extending between the upwardly extending hook flanges on the tie plate and the flange

of the rail to engage and detachably secure the rails in place thereon, said keepers being held in place by frictional engagement with the engaging hook flanges on the tie plates.

9. In a railway track construction the combination with a trough-shaped tie having vertically extending flanges, trough-shaped rail chairs having a horizontal web and downwardly extending flanges secured to the flanges of the rail tie, a tie plate having oppositely projecting hook flanges on the marginal edges of a horizontal web, the downwardly projecting hook flanges on opposite edges of the tie plate being bent into clamping engagement with the web of the and detachably secure the rails in place thereon, said keepers being held in place by frictional engagement with the engaging hook flanges on the tie plate, and insulating means between the rail chair and tie plate fastened in place by the downwardly extending hook flanges on the tie plate.

In testimony whereof, I have hereunto set my hand.

WILLIAM WHIGHAM.
